CONTROL FOR AXMINSTER LOOM TUBE
FRAME CONVEYER SYSTEMSWalter H. Wakefield, Worcester, Mass., assignor
to Crompton & Knowles Loom Works, Worcester,
Mass., a corporation of Massachusetts

Application December 18, 1947, Serial No. 792,396

13 Claims. (Ch. 139—7)

1

This invention relates to improvements in Axminster looms and it is the general object of the invention to drive the greater part of the tube frame conveyor system by a variable speed motor.

Axminster looms ordinarily operate with a conveyor system carrying a large number of tube frames extending between endless chains which are trained around sprocket wheels on a so-called pullover shaft. This shaft is given an angular motion for each tuft forming operation of the loom, and when the loom is operating three-shot the shaft moves every third pick or weft laying beat of the loom.

In some Axminster looms the pullover shaft is able to move the entire conveyor system, but in wide looms the tube frame conveyor system is very heavy and it is desirable to drive a small part only of the system by the pullover shaft and drive the greater part of it by a supplementary motor. Under these conditions the motor must be regulated to drive its part of the system at the same average speed as that at which the shaft drives its part. It has been common practice in the past few years to form the conveyor chains with wells which by their variation in depth open and close switches which stop and start a conveyor system driving motor. In such an arrangement the motor is idle for a period of several dozens of picks of the loom and then is active for a period during which it moves the conveyor system at a relatively high speed. Furthermore, the motor when starting picks up its stationary load with an abrupt start which strains the driving parts and subjects them to considerable wear.

It is an important object of the present invention to drive a large part of the conveyor system by a motor which runs continuously during loom operation but at a speed which varies in such manner that its average speed will move the system at the rate required by the pullover shaft.

The conveyor system is composed of a short tight section driven by the pullover shaft and a longer tight section driven by the motor. These sections are connected together by slack portions forming wells. It is a further object of the invention to regulate the conveyor system motor by a variable resistance unit one part of which is moved by the pullover shaft in time with one of the tight sections and the other part of which is moved by the motor in time with the other tight section. In this way the control is derived from the tight sections and the wells which are undriven parts of the system can be short and shallow.

2

The invention can be carried into effect by either direct or alternating current motors. When a direct current motor is used the changing resistance can be in series with the field of a shunt wound motor, and in the case of a polyphase alternating current motor changing resistances can be in series with the windings of a rotor. In either instance the periodic advance of the pullover shaft will change the resistance unit to cause the conveyor system motor to run at a higher than average speed, and during the time the pullover shaft is at rest that part of the aforesaid resistance unit which moves with the conveyor system motor has an opportunity to restore itself to normal position relatively to the other part of the unit. In this way one part of the resistance unit advances periodically and the other part then moves at an increased rate to catch up with the first part.

It is a still further object of the invention to construct the resistance unit so that the pullover shaft and conveyor system motor can be reversed.

With these and other objects in view which will appear as the description proceeds, my invention resides in the combination and arrangement of parts hereinafter described and set forth.

In the accompanying drawings, wherein two forms of the invention are illustrated,

Fig. 10 is a diagrammatic view showing the relation of the speeds of the two tight sections of the tube frame conveyor system.

Referring particularly to Fig. 1, the loom proper is designated at L and the tube frame conveyor system at CS. The loom is provided with a driving motor LM connected by gearing 20 to a main shaft 21 to which a cam 22 is secured. The latter rocks a lever 23 the upper end of which is pivoted to upper and lower rods 24 and 25, respectively. These rods extend forwardly and are connected to rocking levers 26 and 27, respectively, which move angularly around a pullover shaft P. Each of the levers 26 and 27 is provided with a feed pawl not shown but well understood, and a control pawl shield lever 28 moved by a hand lever 29 and link 30 determines which of the feed pawls shall be in operative position. When lever 28 is up it disables the pawl of lever 26 and permits the pawl of lever 27 to move to operative position so that upon backward movement of the rods 24 and 25 the shaft P will turn in a counter-clockwise direction as viewed in Fig. 1. If lever 28 is down shaft P will turn in a clockwise direction each time the upper part of lever 23 moves rearwardly.

When the loom is weaving a three shot fabric the shaft P will be advanced every third pick of the loom and ordinarily in a time which is slightly more than half the time of one pick. The shaft then remains at rest until lever 23 moves rearwardly again. The loom also has a lay 31 and tuft cutting mechanism part of which is indicated at 32.

The overhead conveyor system CS is supported by a framework 35 including an upper horizontal I-beam 36 which supports an elongated horizontal shaft 37. The latter is provided with a number of worms 38 which mesh with and drive worm wheels 39, 40, 41 and 42 secured to cross shafts 43, 44, 45 and 46, respectively. Each cross shaft is provided with a pair of sprocket wheels 47 meshing with two endless chains 48 and 49, one at each side of the loom, which carry tube frames T.

The conveyor system includes two tight sections which are permitted to have a slight amount of independent motion relatively to each other by two loose sections. The upper tight section TS driven by shaft 37 comprises the greater part of the length of the system and extends from shaft 45 to the right, Fig. 1, around idler sprockets 50, up to and over shaft 43, and then to the left over framework 35 to the sprocket 47 on shaft 46.

The other tight section PS is much shorter than the section TS and is driven by the pullover shaft P. The lower parts of section PS extend around sprockets secured on the pullover shaft one of which is shown at 51. The upper right hand part of section PS, Fig. 1, meshes with a freely turning sprocket 52 supported on framework 35. The upper left hand part of section PS meshes with a second sprocket 53 secured to a cross shaft 54 rotating freely on framework 35 independently of shaft 37.

A small chain 55 meshes with sprockets 56 turning with sprockets 52 and 53, one of the sprockets 56 being shown in Fig. 3. Sprockets 52 and 53 therefore turn in unison and in the same direction, and shaft 54 turns with them. These sprockets are turned by a force derived

from pullover shaft P and transmitted by tight section PS. For reasons to be pointed out hereinafter it is important to note that conveyor chain sprocket 53 and shaft 54 turn in timed relation with the pullover shaft P independently of the tight section TS of the conveyor system and shaft 37.

The two tight sections of the conveyor chain system are loosely connected by front and back 10 freely hanging wells WF and WR. The length of these wells is not important, but for brief recurring intervals they should permit movement of the pullover section PS at a rate which is relatively faster than the rate at which the tight 15 section TS moves.

The conveyor chains 48 and 49 progressively move the tube frames T through a transfer station S below the shaft P. When a tube frame, such as T', Fig. 1, reaches the transfer station 20 it will be moved by mechanism not shown down to tuft forming position and then back to the conveyor chains while shaft P is stationary. The latter shaft will then be given an angular movement, which may be $\frac{1}{6}$ of a turn, to move the 25 next tube frame to the transfer station.

The matter thus far described is of common construction as shown in prior Patents Nos. 1,512,057 and 1,553,558 and of itself forms no part of the present invention except as noted 30 hereinafter.

In carrying the preferred form of the invention into effect I drive the shaft 37 by a shunt wound direct current motor DM having an armature A and a field coil F. The motor runs continuously during loom operation but at a varying speed caused by changes in the strength of the magnetic field. The motor has a built-in gear reducer not shown and is connected to shaft 37 by gearing 57.

40 The strength of the electric current flowing through field coil F is regulated by a variable resistance speed control unit CU including a drum resistor member 60 and a sweep arm member 61. Both members are mounted on shaft 54, member 60 being secured to and turning with the shaft and member 61 rotating freely on the shaft.

A drum 62 forming part of member 60 is keyed 50 to shaft 54 and is made of insulating material supporting a series of contact buttons 64 arranged concentrically around shaft 54. Resistance elements 65 are connected to the buttons to be in series and are contained within the drum. Two collector rings 66 and 67 extend 55 peripherally around the drum and contact stationary brushes 68 and 69, respectively. Right hand button 64, Fig. 4, is connected electrically to ring 66 while the left button is connected to ring 67. Since the drum resistor member 60 is fast with respect to sprocket 53 and shaft 54 it is turned by power derived from the pullover shaft P and has an advance movement each time the tight conveyor section PS moves another tube frame to the transfer station.

65 The sweep arm member 61 comprises a resilient contact arm 70 the free end of which engages the buttons 64. Arm 70 is secured to a disk 71 made of insulating material and having thereon a peripheral collector ring 72 electrically 70 connected to arm 70 and engaging a stationary brush 73. A small sprocket wheel 74 is secured to disk 71 and meshes with a tight chain 75 trained over a sprocket wheel 76 rotatable on framework 35. A sprocket wheel 77 of the same size as wheel 74 is secured to the shaft 46, Figs.

1 and 2, and meshes with the chain 75. Chain 75 causes sweep arm 70 to turn in timed relation with the tight conveyor section TS and motor DM.

In Fig. 5 which shows the circuits for motor DM power line L' is connected to one side of field coil F through a shipper controlled switch 80 which is closed during loom operation but open when the loom is not running. Switch 81 in switch box SB, Fig. 1, is controlled by handle 29 and is connected to the other power line L2. A reversing switch 82 is connected between lines L' and L2 and the armature A and may conveniently be located in box SB under control of handle 29.

In the operation of the matter thus far described it may be assumed that the pullover shaft P is driven in such a direction as to cause counter-clockwise angular motion of resistance member 60, Fig. 1, each time a new tube frame is moved to the transfer station, and that shaft P is starting to rock clockwise. Switches 80, 81 and 82 will be in their full line positions in Fig. 5 and motor DM will be running at low speed because sweep arm 70 is in such position as to cut out most of the resistance in circuit with the field coil F. At the start of the turning movement of shaft P the sweep arm 70 and resistance member will be in what may be considered their normal relation shown in Figs. 4 and 5 and position I of Fig. 6 with the sweep arm moving at its minimum rate of angular motion. Upon completion of the angular movement of shaft P, which occurs while sweep arm 70 is almost at rest or moving very slowly, the resistance member will have advanced to the dotted line position of Fig. 5 and position II of Fig. 6. A greater amount of resistance will now be in series with the field coil, thereby increasing the speed of motor DM and causing the sweep arm to move to the left at an increased rate.

Position III of Fig. 6 shows the sweep arm continuing to move in a left hand direction while the resistance member remains stationary in its new position. As motion of the sweep arm continues the amount of resistance in series with the field coil diminishes to decrease the speed of motor DM. The sweep arm will continue to move until the parts assume the position shown at position IV in Fig. 6 where the resistance member and sweep arm are back in the same relative position which they had at the start of the operation, as shown in position I, Fig. 6. The speed of the motor and the resistance are such that by the time the two members 60 and 61 of the resistance unit reach the last position described the pullover shaft P will ordinarily have another angular motion and the operation will be repeated. During constant speed running of the loom the arm 70 will sweep over a given group g of buttons which may be considered the normal range of its motion relatively to the resistance.

Fig. 10, which applies to both forms of the invention, indicates graphically the times of operation of the pullover shaft and its relative speed with respect to the varying speed of the motor DM. The horizontal line fe represents time of the loom and the vertical line fh represents instantaneous speeds of the pullover shaft and motor DM and the two tight parts PS and TS of the conveyor system. The curve k represents the first rocking of shaft P starting at the beginning of the first pick of a three-pick cycle and completed before the end of that pick. The pullover shaft and tight section PS then remain

idle for the balance of the three picks. The line m represents the speed of the motor DM and the tight part TS of the conveyor system which it moves.

At the beginning of the first pick the motor speed will be low, but as soon as the resistance advances ahead of sweep arm the field current is weakened and the speed of the motor DM increases to a maximum occurring about at the time curve k falls back to zero. The resistance member is now at rest and the motor, the sweep arm and section TS move at a rate faster than their average rate but at a rate which decreases as continued running of motor DM causes the sweep arm to reduce the resistance in series with field coil F. Motor speed will drop to its low value occurring when the pullover shaft again rocks as indicated by curve k'. The time of operation of motor DM, that is, three picks of the loom, together with its changing rates as it runs, moves the tight section TS the same amount that section PS is moved by the pullover shaft.

The description just given assumes that the loom runs at constant speed and that the range of buttons over which arm 70 sweeps is the group g, position II, Fig. 6. It will be noted that there is at least one reserve button on each side of range g.

The amount of resistance will be so chosen as to cause the motor DM to adjust itself to some variation in the speed of the loom and the length of the intervals between successive rockings of shaft P. If, for instance, the length of the intervals between rocking of shaft P should be slightly increased due to slower loom speed sweep arm 70 will move to the left of its position shown at IV, Fig. 6, and engage one of the reserve buttons contact with which cuts still more resistance out of the field circuit, thereby causing motor DM to run at a rate below its normal low rate. This allows time for the next rocking of shaft P. Under these conditions the sweeping range of arm 70 will be shifted to the left of range g.

If, on the other hand, the length of the intervals between rockings of shaft P should be reduced due to a temporary increase in loom speed, the resistance will advance before arm 70 reaches the left end of range g, and the range of the group of buttons over which arm 70 sweeps will be shifted to the right of range g, causing faster than normal running of motor DM.

Within limits of loom speed variation the sweep arm will find its correct range of motion with respect to the buttons 64 and the resistance. It will be seen that the shaft P and the resistance member 60 by their periodic angular movements serve as a pacemaker and the sweep arm 70 driven by the motor serves as a follower which always tries to catch up to a given relative position with respect to the resistance member before the latter is again moved.

The foregoing description assumes only one direction of turning of shaft P and motor DM. When handle 29 is moved to reverse the direction of turning of the pullover shaft switches 81 and 82 will shift to the dotted line positions of Fig. 5, and the resistance will be moved to the right of the sweep arm, Figs. 1, 4 and 6, whenever shaft P rocks. The operation already described will be the same except reversed.

At the end of the reversal it will usually be desirable to weave a non-pile heading. This is done by moving handle 29 to its middle or neutral position in which switches 81 and 82 are open and motor DM is idle.

In the modified form of the invention a poly-phase induction motor IM is used having a rotor 90 wound with three coils 91, 92 and 93, as shown in Fig. 9. Three resistances are provided for the coils and are indicated at R', R2 and R3. When resistance is introduced into the circuits of the windings of a wound rotor the speed of the latter is reduced, this condition being the opposite of that already described for the field of motor DM. In the modified form, therefore, resistances will be cut out of the rotor coil circuits as the pull-over shaft advances.

The small chain 75 and its sprocket wheels 74, 76 and 77 will be the same as in the preferred form of the invention, and the shaft 54 will have mounted thereon a variable resistance speed control unit 99 comprising a resistance drum member 100 and a sweep arm member 101, see Figs. 7 and 8.

The drum 100 is secured to shaft 54 and has contact buttons 102 arranged in three groups 103, 104 and 105 connected respectively to the three resistances R', R2 and R3 similar to resistance of member 60. Drum 100 has six peripheral collector rings 106-111 arranged in three pairs, and the rings of each pair are connected to the end buttons of the corresponding group 103-105, see Fig. 9. The rings 106-111 engage brushes 112-117, respectively, mounted on a support 118 made of insulating material.

The sweep arm unit 101 has a disk 120 made of insulating material and having secured thereto three electrically connected sweep arms 121, 122 and 123. Disk 120 is secured to sprocket wheel 74 and turns in time with the tight section TS.

The wiring for the modified form of the invention is shown in Fig. 9. Main power lines L3, L4 and L5 are connected by switch 125 to wires 126, 127 and 128 which supply power for both the loom motor LM and the motor IM. A switch 130 controlled by shipper mechanism designated generally at 131 is operative when the loom is running to connect wires 126, 127 and 128 to wires 132, 133 and 134, respectively, leading to a reversing switch 135 from which wires 136, 137 and 138 lead to the stator 140 of the motor IM. When the loom is not running switch 130 is open. Switches 142, 143 and 144 are connected by rod 145, under control of handle 29, to the blades of switch 135. These switches are open when lever 28 is in neutral position and shaft P is at rest for the weaving of a non-pile heading. Motor IM can run only when the loom runs and when pile fabric is being woven.

In the operation of the modified form of the invention it may be assumed that the tight sections PS and TS move as first described in connection with the preferred form. At each angular movement of shaft P the resistance member 100 will move counter-clockwise, Fig. 8, while the sweep arms are almost at rest. This motion of member 100 will cut resistance out of the circuits of the coils or windings 91, 92 and 93, and motor speed will increase. Member 101 will thereupon move faster due to increased speed of the tight section TS, and eventually catch up with the member 100. The operation is in general the same as that described for the preferred form of the invention, but switches 142, 143 and 144 are connected to the ends of their resistances away from which the sweep arms 121, 122 and 123 move due to increased motor speed. In the preferred form the opposite condition exists, that is, switch 81 is connected to that end of the re-

sistance R, see Fig. 5, toward which sweep arm 70 moves.

Reversal of switch 135 causes motor IM to reverse due to reversal of rotation of the field of magnetic force in the stator, and at the same time reverses switches 142, 143 and 144. If the reversal should occur when the members 100 and 101 are in the position suggested in Fig. 9, motor IM would immediately start to run faster and the sweep arms would be moving clockwise when the resistance member was moved in the same direction by the pullover shaft. This same condition would also exist in the preferred form of the invention.

From the foregoing it will be seen that the invention provides means by which the two tight sections of the conveyor system jointly operate a speed control unit for the motor which drives the long conveyor section TS. The pullover shaft sets the pace and determines the average speed or rate of movement of section PS, and the control unit causes the motor DM or IM to drive section TS at the same average rate. The motor control includes a resistance member and a sweep arm member, one member being operated by a force derived from the pullover shaft and the other being operated by the motor. While in each form of the invention the resistance member has been shown as operated by the pullover shaft and the sweep arm member by the conveyor system motor, I do not wish necessarily to be limited to this particular arrangement for driving the two members of the speed control unit. The slack wells are provided to permit a slight relative motion of the tight sections with respect to each other, but they do not in any way enter into the control of the motor and they can be short and shallow. The pullover shaft when operating will intermittently feed chain into and lengthen one well while drawing chain from and shortening the other well, and the chain driving motor will draw chain from the one well and feed chain into the other well, the wells permitting the chain section TS to be driven at an average speed equal to that of section PS. In the preferred form of the invention the periodic movements of the pull-over shaft cut resistance into the circuit of the field coil of the direct current motor to increase speed of the latter and enable the sweep arm to catch up with the resistance member. In the modified form of the invention the reverse relation with respect to motor speed and resistance requires that the pullover shaft when moving reduce the resistance in series with the windings of the rotor. In both forms of the invention the conveyor system motor is temporarily speeded up when the pullover shaft rocks and then gradually diminishes its speed until the pullover shaft again rocks. Provision is also made for reversing the direction of movement of the conveyor system, this part of the invention including two connectors for each resistance and the switch means which allows current to flow through one or the other of the ends of the resistance, depending upon the direction in which the system is moving.

Having thus described my invention it will be seen that changes and modifications may be made therein by those skilled in the art without departing from the spirit and scope of the invention and I do not wish to be limited to the details herein disclosed, but what I claim is:

1. In an Axminster loom provided with a tube frame conveying system having two driven sec-

tions, pullover mechanism periodically moving one of said sections, a continuously running motor having driving relation with the other section only and separate from the loom, and speed control means for the motor jointly controlled by said two driven sections causing the motor to drive said other section at an average speed equal to the average speed at which the pullover mechanism moves said one section.

2. In an Axminster loom provided with a tube frame conveying system having two driven sections connected by two slack sections, pullover mechanism periodically moving one of said driven sections and lengthening one slack section and shortening the other slack section, a continuously running variable speed motor separate from the loom driving the other driven section, and speed control means for the motor operated jointly by said driven sections and including a variable resistance causing the motor to drive said other driven section to shorten said one slack section and lengthen said other slack section and drive said other driven section at the same average speed at which the pullover mechanism moves said one driven section.

3. In an Axminster loom provided with a tube frame conveying system having two driven sections, pullover mechanism periodically moving one of said sections, driving means separate from the loom operating continuously during loom operation to move the other section only, and control means for varying the speed of said driving means controlled jointly by said sections and tending to cause the driving means to move said other section at an average speed equal to the average speed at which the pullover mechanism moves said one section.

4. In an Axminster loom having a driving motor and provided with a tube frame conveying system having two driven sections, pullover mechanism operated by the driving motor periodically moving one of said sections, an electric motor separate from the driving motor for the other section driving the latter continuously, and electric speed control means for the electric motor including two rotary members moved by forces derived from the pullover mechanism and electric motor causing the latter to operate at variable speeds to move said other section at the same average speed as that at which the pullover mechanism moves said one section.

5. In an Axminster loom having a tube frame conveying system including a tight section forming part of said system and having periodic movements and a second tight section forming another part of said system, an electric variable speed motor for said second section only continuously driving the latter while the first section moves and is also at rest, and electric speed control means for the electric motor including a rotatable part moving angularly and periodically with the first section and including a second rotatable part moving continuously and angularly in timed relation with the second section, said control means causing the motor to move the second section at an average speed equal to the average speed of the first section.

6. In an Axminster loom provided with a conveyor system having two driven sections each movable to advance tube frames to a transfer station, pullover mechanism periodically moving part of one of said sections toward said station and determining the average speed at which said one section moves, variable speed driving means separate from the loom causing part of the other

section to move continuously toward said station, and means controlled jointly by the pullover mechanism and driving means causing the latter to move said other section at said average speed.

5. In an Axminster loom tube frame conveyor system having one section thereof driven periodically by a pullover shaft and having another section thereof driven by a variable speed

10 continuously running electric motor, a speed controller for the motor including a rotary member driven by a force derived from the pullover shaft and a second rotary member driven by a force derived from the motor cooperating with the 15 first member to cause the motor to run at variable speed and move said other section at an average speed equal to the average speed at which the pullover shaft moves said one section.

8. In an Axminster loom tube frame conveyor 20 system having one section thereof driven periodically by a pullover shaft and having another section thereof driven by a variable speed continuously running electric motor, a speed controller for the motor including a variable resistance 25 jointly controlled by said sections and causing the motor to run at variable speed and move said other section at an average speed equal to the average speed at which the pullover shaft moves said one section.

30 9. In an Axminster loom tube frame conveyor system having one section thereof driven periodically by a pullover shaft and having another section thereof driven by a variable speed continuously running electric motor, a speed controller for the motor including a resistance member 35 moved by the pullover shaft and a contact member moved by the motor cooperating with the resistance member to cause the motor to run at variable speed and move said other section at an average speed equal to the average speed at which the pullover shaft moves said one section.

40 10. In an Axminster loom having a tube frame conveying system formed with two tight sections, a pullover shaft moving one of said sections periodically, an electric variable speed 45 motor separate from the loom continuously moving the other of said sections, and a unit for varying the speed of the motor including a resistance moving in timed relation with one of said sections and a contact for the resistance movable relatively thereto in timed relation with the other section, said unit causing the motor to run at variable speed and move the section corresponding thereto at an average rate equal to the average rate of the section corresponding to the pullover shaft.

55 11. In an Axminster loom having a tube frame conveying system including two tight sections movable relatively to each other, a sprocket wheel turned by one of said sections when the latter moves, pullover mechanism to move said one section periodically, a second sprocket wheel moved by the other section when the latter moves, an electric motor driving the second sprocket wheel, and speed control means for the motor including a resistance member moving with one of said sprocket wheels and a contactor moving with the other of the sprocket wheels and cooperating with the resistance member to cause the motor to drive said other section at an average rate equal to the average rate at which the pullover mechanism moves the first section.

60 12. In an Axminster loom having a tube frame conveying system including two tight sections movable relatively to each other, a pullover shaft turned by one of said sections when the latter moves, pullover mechanism to move said one section periodically, a second sprocket wheel moved by the other section when the latter moves, an electric motor driving the second sprocket wheel, and speed control means for the motor including a resistance member moving with one of said sprocket wheels and a contactor moving with the other of the sprocket wheels and cooperating with the resistance member to cause the motor to drive said other section at an average rate equal to the average rate at which the pullover mechanism moves the first section.

65 13. In an Axminster loom having a tube frame conveying system including two tight sections movable relatively to each other, a pullover shaft turned by one of said sections when the latter moves, pullover mechanism to move said one section periodically, a second sprocket wheel moved by the other section when the latter moves, an electric motor driving the second sprocket wheel, and speed control means for the motor including a resistance member moving with one of said sprocket wheels and a contactor moving with the other of the sprocket wheels and cooperating with the resistance member to cause the motor to drive said other section at an average rate equal to the average rate at which the pullover mechanism moves the first section.

70 14. In an Axminster loom having a tube frame conveying system including two tight sections movable relatively to each other, a pullover shaft turned by one of said sections when the latter moves, pullover mechanism to move said one section periodically, a second sprocket wheel moved by the other section when the latter moves, an electric motor driving the second sprocket wheel, and speed control means for the motor including a resistance member moving with one of said sprocket wheels and a contactor moving with the other of the sprocket wheels and cooperating with the resistance member to cause the motor to drive said other section at an average rate equal to the average rate at which the pullover mechanism moves the first section.

75 15. In an Axminster loom having a tube frame conveying system including two tight sections movable relatively to each other, a pullover shaft turned by one of said sections when the latter moves, pullover mechanism to move said one section periodically, a second sprocket wheel moved by the other section when the latter moves, an electric motor driving the second sprocket wheel, and speed control means for the motor including a resistance member moving with one of said sprocket wheels and a contactor moving with the other of the sprocket wheels and cooperating with the resistance member to cause the motor to drive said other section at an average rate equal to the average rate at which the pullover mechanism moves the first section.

11

ond shaft operatively connected to the other section causing movement of the latter when said second shaft turns, an electric continuously running variable speed motor having driving relation with said second shaft, and control means for said motor including a resistance member moving with one of said sections and a contact member moving with the other section and co-operating with the resistance member to cause the motor to drive said second shaft at a rate which will cause the second section to move at an average rate equal to the average rate at which the pullover shaft moves the first section.

13. In an Axminster loom provided with a tube frame conveyor system having two tight sections movable independently of each other and joined by two slack sections and wherein both tight sections are required to move substantially the same distance during an extended period of weaving, means operated by the loom periodically moving one of said tight sections and moving the latter said distance during said period of weaving, a continuously running electric motor separate

12

from the loom operatively connected to the other tight section, and electric means jointly controlled by the tight sections causing the electric motor to move said other tight section said distance during said period of weaving.

WALTER H. WAKEFIELD.
